DENTAL JET PRODUCING KIT

Samuel J. Koch, 999 Green St.,
San Francisco, Calif. 94133

Filed July 12, 1967, Ser. No. 7,778

Term of patent 7 years

(Cl. D24—1)

FIG. 1 is a perspective view of a dental jet producing kit showing my new design.

FIG. 2 is a side view thereof.

FIG. 3 is a top plan view thereof.

I claim:

The ornamental design for a dental jet producing kit, substantially as shown.
